FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

COIN-HOLDER OR OTHER RECEPTACLE.

1,209,829.

Specification of Letters Patent. Patented Dec. 26, 1916.

Application filed December 5, 1914. Serial No. 875,569.

To all whom it may concern:

Be it known that I, FRANZ A. FULLER, a citizen of the United States, residing in the city of Newark, in the county of Essex and State of New Jersey, have invented certain new and useful Improvements in Coin-Holders or other Receptacles, of which the following is a full, clear, and exact description, such as will enable others skilled in the art to which it pertains to make, construct, and use the same, reference being had to the accompanying drawings, and to numerals of reference marked thereon, forming a part of this specification.

The invention relates generally to improvements in holders or receptacles for coins or other articles, the principal purpose of the invention being to provide a novel construction of holder or receptacle which is especially adapted for the placing of coins therein and can be conveniently carried in the pocket, the holder or receptacle being provided with a double lid or cover, one of which (the outer) can readily be opened, but the other (the inner) while being easily opened, requires a key or similar device to be inserted on the part of the operator before the inner lid or cover can be opened.

The present invention consists primarily, in the novel coin holder or receptacle hereinafter set forth, and, furthermore, this invention consists in the various novel arrangements and combinations of parts, all of which will be described in detail in the following specification, and then finally embodied in the clauses of the claim.

The invention is clearly illustrated in the accompanying drawings, in which—

Figures 1 and 2 represent respectively, a side and a rear edge view of a coin holder or receptacle, made according to the principles of this invention, the lids or covers of the holder or receptacle being represented in their closed positions. Figs. 3 and 4 represent respectively, a side view and a top edge view of the said holder or receptacle, with the outer lid or cover shown in its raised or opened position. Fig. 5 represents a longitudinal vertical sectional view representing the one lid or cover in its opened or raised position, and the inner lid in its locked position with the main body of the receptacle. Fig. 6 represents a sec-

tional view of the inner lid. Fig. 7 represents a perspective view of a releasing spring employed in connection with the inner lid or cover; and Figs. 8 and 9 represent respectively, side and edge views of the key employed in opening the inner lid or cover.

Similar numerals of reference refer to like parts throughout the specification and drawings.

In the said drawings, 1 represents the complete holder or receptacle, the same comprising a main body 2, preferably formed with an upper bead or projection 3 and a lower bead or projection 4, substantially as illustrated. The lower end of said receptacle 1 is closed by means of a cap 5, and its upper end forms an opening or mouth 6. The said body 2 may be provided on its outer surface with a suitable covering 7, which may be leather, celluloid or any other suitable material, or, if desired, such covering may be entirely dispensed with. Suitably secured in the sides of said body 1 is a pintle 8, upon which is pivoted by means of suitably disposed perforated ears or lugs 9 a lid or cover 10. Within the chambered portion of said lid or cover 10 is suitably secured near its pivotal portion a shoe 11, the said shoe being formed with a forwardly-extending member or stud 12. That the said lid or cover 10 may be positively retained in either its closed or open relation with the mouth or opening 6 of the said body 2, a suitably constructed flat spring 13 has its upper end portion in slideable engagement with the free end of the said stud 12. The said spring 13 is provided with a tongue 14 or other suitably-formed holding member provided, preferably, with a bent or curved portion 15, which is slipped into and is securely held in a loop or other suitably-formed holding means 16, extending inwardly from the inner surface of the back edge of the body 2. The opening or closing movements of the said outer lid or cover will be clearly understood and it will be seen that the lid is held in its closed relation with the mouth portion 6 without the use of a holding catch.

The inner lid or cover 17 is provided at or near its rear end portion with a pair of downwardly extending and perforated ears

or lugs 18, by means of which said inner lid is pivotally arranged upon the previously-mentioned pintle 8 between the ears or lugs 9 of the outer lid or cover 10, the lid or cover 17 being provided with a slot or opening 19, into which the shoe 11 and the stud 12 of the outer lid or cover 10 extend, so as not to interfere with the pivotal movements of the inner lid 17. The said inner lid 17 is made at its forward end with a downwardly-extending portion 19', which, when the lid is in its closed position in the mouth 6 of the body 2, presses directly upon the upper end 20 of the releasing spring 21, said portion 19' passing between the spring 21 and the inner surface of the front edge portion of the box, a rearwardly extending nosing or holding catch 22 on said portion 19' being forced into locking engagement with the receiving portion 23 of the spring 21. The spring 21 beyond the receiving portion 23 is bent at an angle toward the inside of the receptacle, said bent portion 24 being also provided with a receiving portion or aperture 25 to be presently described.

The main body 2 is provided in the narrow front edge portion with an opening 30, and a holding member or loop 31, forced out from the metal, as illustrated in the drawings, or otherwise connected with the said front edge portion upon the interior surface thereof, as will be clearly understood. In this holding member or loop is slipped and held therein, by means of a bent portion 32, the holding tongue of said releasing spring 21.

The inner lid or cover 17 is further provided with a slot or opening 26, through which the coin to be placed in the receptacle or holder 1 is passed. This slot or opening 26 is normally closed by means of a resilient guard, which may consist of a piece of felt, leather or other suitable material 27, secured to the under side of said lid 17, by means of suitable holding-lugs 28 formed integral with said lid 17. This arrangement enables the coin to be readily inserted through the slot or opening 26, and at the same time, prevents the withdrawal 50 of the same through said slot or opening.

An opening 29 of any desired form to receive a key 33 or the like, is located near the front end of the lid 17, and directly above the receiving portion or aperture 25 of the bent portion 24 of the flat spring 21, when the lid 17 is in locked relation with said spring 21.

The key 33, preferably formed from a single piece of suitable material, is provided 60 with an engaging portion 34, angular in cross-section and of a shape corresponding with the opening 29 located near the front end of the lid 17, said engaging portion being designed to be received by said opening 29 and to extend into the receiving por-

tion or aperture 25 of the bent portion 24 of the releasing spring 21, and there to engage with the front edge of said aperture 25.

To raise the inner lid or cover 17, the outer lid 10 is first opened or raised in the usual manner, and its position then is such that the inner lid 17 can be released from its holding engagement with the spring 21, when the engaging portion 34 of the key 33 is inserted in said opening 29 and engages with the front edge of the aperture 25 and given a slight turn, thereby causing the spring 21 to be moved in the direction indicated by the arrow and withdrawing the rearwardly-extending nosing or holding catch 22 out of locking engagement with the receiving portion 23 of said spring 21.

It is not my intention to limit the invention to the precise details of construction shown in the accompanying drawings, it being apparent that such may be varied without departing from the spirit and scope of the invention.

I claim:

1. A holder or receptacle for coins or other articles, comprising a main body having a mouth, an outer lid arranged over said mouth, a spring in said body in engagement with said outer lid, an inner lid arranged between said outer lid and the mouth of said body, provided with a coin-receiving opening and a key-receiving aperture, a catch on said inner lid, and a releasing spring in said body normally in holding engagement with said catch, said releasing spring being provided with a free end extending into the inner lid, said free end being provided with an aperture, said aperture being in alinement with the key-receiving aperture of said inner lid to receive a key for releasing the free end of said spring from the inner lid.

2. A holder or receptacle for coins or other articles, comprising a main body having a mouth, an outer lid arranged over said mouth, a spring in said body in engagement with said outer lid, an inner lid arranged between said outer lid and the mouth of said body, and provided with a key-receiving aperture, a catch on said inner lid, and a releasing spring in said body normally in holding engagement with said catch, said releasing spring being provided with an offset extending into the inner lid and said offset being provided with an aperture which is in alinement with the key-receiving aperture of said inner lid.

3. A holder or receptacle for coins or other articles, comprising a main body having a mouth, an outer lid arranged over said mouth, a spring in said body in engagement with said outer lid, an inner lid arranged between said outer lid and the mouth of said body, said inner lid being provided with a

coin-receiving opening and a key-receiving aperture, a resilient guard secured to the said inner lid and normally closing said opening, and a releasing spring in said body 5 normally in holding engagement with said catch, said releasing spring being provided with an offset, said offset extending into the inner lid and being provided with an

aperture which is in alignment with the key-receiving aperture of said inner lid.

This specification signed and witnessed
